UNITED STATES PATENT OFFICE.

JAMES A. PARK, OF WHITE HOUSE STATION, NEW JERSEY.

FENCE-MACHINE.

SPECIFICATION forming part of Letters Patent No. 624,532, dated May 9, 1899.

Application filed May 5, 1898. Serial No. 679,782. (No model.)

To all whom it may concern:

Be it known that I, JAMES A. PARK, of White House Station, in the county of Hunterdon, State of New Jersey, have invented 5 certain new and useful Improvements in Fence-Machines, of which the following is a complete specification, reference being had to the accompanying drawings.

My invention relates to improvements in 10 machines for making wire fabrics; and it is particularly designed for interweaving weft-wires diagonally between the warp-wires, so as to make a fabric suitable for fencing purposes.

15 The machine shown in the annexed drawings, while particularly designed for placing the weft-wires upon the warp-wires in a field, may obviously be used for manufacturing the fabric in factories.

20 My improvements consist generally in means for facilitating the forward movement of the machine and for steadyng it in its upright position, in improved means for twisting the weft-wires, and in other details, which 25 will be hereinafter more fully pointed out.

In the accompanying drawings, which illustrate my invention, Figure I is a perspective view of my improved fencing-machine in operative position, the twister-wheels and bobbin-holders being omitted. Figs. II and III are side and top plan views, respectively, of the upper portion of Fig. I, illustrating the manner of moving the machine forward. Fig. IV is a side view of several of the twister-wheels, bobbin-holders, and shafts. Fig. V is a central vertical section, enlarged, through two of the twister-wheels shown in Fig. IV. Fig. VI is a front view of three of the twister-wheels and a pair of bobbin-holders. Fig. VII is 35 a perspective view of two of the twister-wheels. Fig. VIII is a side view of part of the intermeshing cogs of the twister-wheels and the stem of the bobbin-holder in engagement therewith, the latter being shown in cross-section.

40 Fig. IX is a perspective view, partly broken away, of one of the hollow shafts through which the warp-wires extend and which support the twister-wheels. Fig. X is a central longitudinal section through one of the bobs 45 bins and bobbin-holders. Fig. XI is a horizontal section, partly in plan view, taken centrally through the driving-shaft of the ma-

chine. Fig. XII is a section on the line xx of Fig. III. Fig. XIII is a vertical longitudinal section through the upper part of the 55 forward standard of the machine, showing the wire-clutch mechanism. Fig. XIV is a central vertical section through the clutch shown in Fig. XIII. Figs. XV, XVI, and XVII are perspective views of parts of the clutch. Fig. 60 XVIII is a front perspective view of the base of a bobbin-holder. Fig. XIX is a similar view of one of the pivoted dogs for connecting the bobbin-holder to the twister-wheels. Fig. XX is a similar view of one of the bobbin-clamps. Fig. XXI is a similar view of one of the bobbins. Fig. XXII is a section on the line yy of Fig. II, and Fig. XXIII is a section on the line zz of the same figure.

Referring to Fig. I of the drawings, 1 and 2 indicate vertical standards, by which the working parts of the machine are supported. The rear section of the machine consists of a standard 2, longitudinally divided in the plane of the warp-wires, the two parts of the standard having opposing recesses, as shown, on their faces, within which the hollow stationary shafts 3^b , 3^c , and 3^d are clamped by means of bolts 4 passing through the standard and between each pair of shafts. The stationary 75 shafts are each secured to one part of the standard by means of screw-bolts 5, having their heads within and flush with the interior of the shafts and the screw-threaded end passing out through the standard and secured by 80 a nut. The drive-shaft 3^a is mounted in suitable bearings, (shown in Fig. XI,) and this shaft, together with the shafts 3^b and 3^c , forming part of the frame of the machine, are 85 longer than the shafts 3^d .

To the lower extremity of the standard 2 is connected, by any suitable means, such as the bracket 6, (shown in dotted lines,) a semicircular shoe 7, by which the standard is supported. To the rear end of this shoe is rigidly connected a pair of upwardly-curved arms 8, extending in a plane at right angles to the shoe, these arms being provided at their outer extremities with a thumb-screw 9, by means of which they may be drawn together 90 to form a clamp. The arm may be connected to the side of the upright 2 by a suitable brace 10. Beneath the arms 8 and extending at right angles to the machine is a shaft 11,

hinged to the shoe, so as to swing in a vertical plane, and carrying at its outer extremity the wheel 12. A curved link 13 is rigidly connected to the shaft 11 near its outer end and extends between the two parts of the arm 8, the set-screw 9 passing through the opening in the link. By means of the arrangement just described the wheel 12 may be arranged at different angles, so as to maintain the machine in a vertical position under all conditions.

The standard 1 of the forward section of the machine also consists of two parts 14 and 15. This standard may be much shorter than the rear standard 2. As shown in the drawings, the part 15 extends below the part 14, and a large wheel 16, journaled in this extension, supports the standard. Certain of the hollow stationary shafts—as, for instance, the shafts 3^b—are longer than the others and extend forward between the opposing sides 14 and 15 of the standard 1. These shafts pass freely through guides 20, which are secured to the opposite sides of the standards 1 by means of straps 21.

Bolted between the two parts of the upright 1 and at either extremity are metal blocks 22, (shown in section in Fig. XXII,) having vertically-projecting studs 23, upon which are journaled the ends of links or pitmen 24, the latter being held in place by means of set-screws 25 and washers 26. The links 24 are connected by pins 17 to cranks 27, secured to the opposite ends of a vertical shaft 28. The crank-arms 27 are each provided with a series of holes 18 for the reception of the link-pins, so that the movement of the links may be graduated. The shaft 28 is journaled in boxes 29, mounted upon the intermediate stationary shafts 3^b and 3^a and secured to a brace 30, extending between the shafts 3^b. A beveled gear 31, rigidly secured to the upper part of the shaft 28, engages a beveled gear 32, supported in a suitable manner upon the uppermost journal-box 29^a. As shown in Figs. I and XII, the gear 32 has a central bore in its inner face, which engages with a projecting stud 33 upon the side of the journal-box 29^a, and its shaft 34 is supported by an angle-iron 25, secured to the top of the journal-box. A turning crank 36 is connected to the shaft of the bevel-wheel 32. The brace-bar 30 extends between the upper and lower extended shafts 3^b and is connected to the several journal-boxes, so as to make the machine more rigid. Its upper end 37 is curved forward, so as to clear the gear 31, and is secured rigidly to the uppermost shaft 3^b.

It will be seen that by turning the crank 36 the shaft 28 will be rotated and the links 24 will be given a reciprocating motion through the medium of the cranks 27. At each semi-revolution of the shaft 28, therefore, the standard 1 will be forced forward on its wheeled support a distance equal to the diameter of the circle described by the crank-pin 17 from

the position shown in Fig. I, the guides 20 sliding freely over the extended shafts 3^b.

Supported between the opposite sides of the standard 1 upon bolts 38 are a series of 7^a clutches. (Shown in Figs. XIII to XVII, inclusive, and described below.) These clutches slide freely over the warp-wires during the forward movement of the standard 1, but grip the wires whenever the standard commences 7^b to move in the opposite direction. It will be seen, therefore, that the continuous movement of the crank 36 through a complete revolution or a rocking movement will of necessity draw the rear section of the machine 8^a toward the front section, since the latter cannot move backward. In this manner the movement of the machine is greatly facilitated, as the forward and rear parts of the machine are moved separately and steadily 8^b and no tracks are required. The manner of moving the machine forward is clearly indicated in Figs. II and III. By adjusting the crank-pins 17 the movement may be regulated so as to wind the weft-wires at different intervals.

The clutches above referred to (illustrated in Figs. XIII to XVII, inclusive) consist each of a base-plate 40, having a projecting stud 41 at its lower extremity and a clip 42 at the top, and a spring-pawl 43, depending from a bearing-piece 44, the latter being eccentrically mounted upon a bolt 45, which passes through the base-plate and the upright 14 and is secured by a nut 46 upon the outside 100 of the upright. The bearing-piece 44 is surrounded by a boss 47 and the latter in turn by a flange 48. The pawl 43 has on its lower and forward side a flange 49. A coiled spring 50 surrounds the boss 47, its ends resting 105 within the catch 42 on the base-plate and the flange 49 upon the pawl. The end of the pawl normally hangs directly above the pin 41, and the pawl is adjustable vertically by means of the eccentric bearing 44, so as to adapt the 110 clutch to wires of different gage. The warp-wires pass between the pawl and the pin 41, and it will be seen that when the standard 1 is moved forward the pawls will glide over the wires, but will immediately and firmly 115 engage the wires as soon as a backward pull is exerted upon them. The warp-wires are held against the pins 41 in proper relation to each other by means of bolts 51, passing through the standard 1 in advance of and 120 slightly above the pins 41.

The driving-shaft 3^a (shown in perspective in Fig. I and in horizontal section in Fig. XI) is revolvably mounted in a suitable bearing in the standard 2 and in a bearing 55 125 within one of the journal-boxes 29^b. The shaft is provided near its forward end with a worm 56, which is engaged by a pivoted pawl 57, mounted upon a horizontal plate 58, connected with the journal-box 29^b. The worm 130 is provided with stops 59, which come into engagement with the pawl when the shaft has

been rotated to the desired extent. As shown in the drawings, the stops are arranged so that the shaft can only make two and one-quarter revolutions in either direction. The 5 shaft is driven by means of beveled gears 60 and 61, which are operated by a crank 62.

The twister-wheels, as shown in Figs. IV, V, VI, and VII, are each formed with front and rear skeleton plates, the front plate 63 10 being flat and the rear plate 64, as shown, extending outward toward the center. Each of the stationary shafts is provided with a collar 65, by means of which the wheels are maintained upon the shafts. In placing the 15 wheels upon the shafts the collars 65 are first inserted within the respective wheels and the two are then slipped over the end of the shaft. The collar is then secured to the shaft by a set-screw 66. The wheels will then be free 20 to revolve on the shafts and the collars will prevent lateral displacement. The wheel upon the driving-shaft 3^a is rigidly secured to the shaft by means of a key or set-screw.

As shown in the drawings, one tooth is omitted 25 from each of the twister-wheels, its place being supplied by two small separate auxiliary teeth 67, which extend slightly above the pitch-line. I designate the teeth 67 as "separate" teeth because of the fact that they are 30 separate both from each other and from the remaining cog-teeth. A web or flange projection 68, arranged in rear of the gear-teeth, extends across the space between each of the auxiliary teeth 67 and the adjacent cog. The 35 opposed faces 69 of the webs, and also the faces of the teeth 67, are curved to conform to the shape of the normal gear-teeth. The auxiliary teeth are thinner than the others, and the teeth 70 of the adjacent gear, which 40 intermesh with the auxiliary teeth 67, may be partly cut away, as shown at 71, while the front part 72 of each of these teeth is of normal shape. The front plate of each of the 45 twister-wheels is provided with rectangular openings 73, arranged on either side of the axis and in line with the space 74 between the auxiliary teeth 67.

The bobbin-holder or "twister" consists of a base-plate 75, having curved upper and 50 lower edges 76 and 77, respectively, a tubular extension 78, projecting rearwardly from the center of the plate, a pair of parallel forwardly-projecting arms 79, arranged upon one side of the plate, and a similar pair 80 upon 55 the opposite side. The plate is also formed with two curved oblong openings 81, arranged near the top and bottom, as shown. Each pair of arms 79 and 80 is provided with registering perforations 82 midway of the arms 60 and similar perforations 83 at the ends. In Fig. XIX, I have shown a dog consisting of a 65 bar 84, having a longitudinal groove 85, a pair of perforated ears 86, projecting from one end at an angle to the bar, and a peculiarly-formed head 87, projecting in a plane parallel to that of the ears 86. The head, as shown, consists of a part arranged at an angle to and

projecting partly above the bar 84, its outer surface 88 being curved or inclined and the faces 89 and 90 being straight. A narrow 70 flange 91, having its outer face in the same plane as the face 90, extends downwardly from the bar. Two of these dogs are connected to the arms 79 and 80, respectively, by means of pivot-pins passing through the perforated ears 86 and the perforations 82 in the arms. When the dogs are in place, their heads will swing into the openings 81 in the base-plate, as shown in Figs. V and VI, the flange 91 limiting the movement of the dogs. 75 The dogs are normally held in this position by means of springs 92, which are wound around the pivot-pins 93, one end of the spring resting within the groove 85 and the other end of the spring being hooked around 80 the stud 94 upon the end of a spool-clamp 95, one of which is pivoted in the ends of each pair of arms 79 and 80. It will be seen that the springs 92, while normally forcing the dogs into the openings 81, will also press the 85 spool-clamps 95 toward each other. These clamps are each formed with a stud 96, which projects into the opening in the bobbin 97, and a flange 98, which presses against the end of the bobbin with sufficient force to prevent the 90 spool from turning loosely and too freely unwinding the weft-wire. The wire is fed from the bobbin through the tubular stem 78 in the rear of the bobbin-holder. This stem I prefer to fit with a screw-threaded bushing 99, of brass 100 or other metal different from the weft-wire, so as to avoid friction as much as possible. This bushing is formed with a flange 100. As shown in Fig. VIII, the stem 78 is hexagonal in cross-section, the sides 101 and 102 being 105 adapted to fit against the wheels within the spaces between the cogs and the remaining sides being formed in the shape of two cogs with their bases abutting. This stem is adapted to fit within the space 74 between the auxiliary teeth 67, and when the wheels intermesh at that point, as shown in Fig. VIII, the curved sides of the stem 78 will cut the cogs of the adjacent wheels upon the pitch-line. 110

In assembling the machine the extensions 78 of the bobbin-holders are placed within the spaces 74, the base-plate of each bobbin-holder lying next to the flat front faces of the two adjacent gear-wheels. When the spaces 74 115 are in alignment, the heads 87 of the dogs will project through the openings 81 in the base-plate of the bobbin-holder into the rectangular openings 73 of the adjacent twister-wheels, as shown in Figs. V and VI. In this position 120 the bobbin-holder will be anchored by stationary disks 105 upon the shafts which are fitted close to the base-plate of the bobbin. The disk upon the driving-shaft 3^a is secured to the standard 2 by a sleeve, as shown, while 125 the disks upon the stationary shaft are secured by set-screws to said shaft. These disks are cut away on their upper and lower edges 106 in the arc of a circle corresponding 130

with the curvature of the outer walls of the openings 81 in the base-plates of the bobbin-holders. The bobbin-holder base-plate is in width about equal to the distance between two adjacent shafts, and the edges 76 are formed in the arc of a circle whose radius is approximately equal to the distance between the center of one shaft and the outside of an adjacent shaft.

- 10 It will be seen that when the wheels are in the positions shown in Figs. V and VI the dogs are maintained within the openings in the base-plate and twister-wheels only by the tension of the springs 92; but if the upper gear A in Fig. VI be assumed for the purposes of illustration to be the driving-gear rotating in the direction of the arrow the wall of the lower opening 73 in this gear coming into contact with the inclined surface 88 of the dog will force the latter out of engagement with said opening, whereas the wall in the upper opening of the gear B below coming into contact with straight face 89 of the lower dog will draw the bobbin-holder forward until the face 90 of the dog passes under the disk 105, adjacent to the wheel B. The bobbin-holder will therefore be disengaged from the upper wheel A and will be carried around by the wheel B, being held in engagement therewith by the flange 105 and the flange 100 upon the stem 78. In a similar manner the lower bobbin-holder will be carried around by the wheel B, and the weft-wires will be twisted around the warp-wire 35 passing through the shaft upon which the wheel B is mounted in the usual way. By reversing the direction of the wheels the bobbins instead of passing around the wheel B will pass around the adjacent wheels.
- 10 As stated above, I prefer to rotate the shafts about two and one-quarter times in each direction in order to twist the wires twice, the quarter-turn being allowed to compensate for backlash in the gears. This movement is limited by the worm 56, pawl 57, and stops 59. (Shown in Fig. XI and previously described.)

In operation after the machine has been moved forward a step in the manner already described by turning the crank 36 the gears 50 are operated to twist the weft-wires upon the warp-wires by turning the crank 62. The machine is then moved forward another step and the gears turned in the opposite direction to effect the twisting of the weft-wires upon the adjacent warp-wires, and so on.

It will be noticed that in my machine the bobbin-holders or twisters are in front of the twister-wheels and that the weft-wires are fed out centrally through the tubular stems 60 78, which at all times firmly rest within the spaces formed in the gear-teeth. At the time when the greatest lateral strain is exerted upon the bobbin-holder the stem, it will be noted, is always held between the two gears. 65 By this construction much friction is avoided and the twisters operated positively.

The auxiliary teeth 67 are not necessary

except on the top and bottom wheels or in case an intermediate bobbin-holder is omitted for some purpose. They are intended 70 particularly to intermesh with the adjacent gears when the stem 78 is missing, so that all the wheels will turn together.

What I claim is—

1. In a wire-fence machine, the combination with a rear shaft-supporting section, and a forward section movable in relation thereto, of means for moving both sections forward by independent steps, substantially as set forth. 75
2. In a wire-fence machine, the combination with a rear shaft-supporting section, and a forward section, of guides fixed to one section and along which the other section is movable, substantially as set forth. 85
3. In a wire-fence machine, the combination with a rear shaft-supporting section and guide-shafts carried by said section, of a forward section movable along said guide-shafts, and mechanism for moving said sections forward by independent steps, substantially as set forth. 90
4. In a fence-machine, the combination with a rear shaft-supporting section and guide-shafts carried by said section, of a forward section movable along said guide-shafts, a crank upon one section, and a link extending between said crank and the other section, substantially as set forth. 95
5. In a wire-fence machine, the combination with a rear shaft-supporting section, and guide-shafts carried by said section, of a forward section carrying clutches, and movable along said guide-shafts, and a crank-and-link connection between said sections, substantially as set forth. 105
6. In a wire-fence machine, the combination with a rear shaft-supporting section carrying guide-shafts, and a forward section movable upon said shafts, of clutches carried by the forward section and adapted to engage warp-wires when said section is in its advanced position, and a crank-and-link connection between the sections, substantially as set forth. 110
7. In a wire-fence machine, a rear shaft-supporting section, carrying stationary guide-shafts, a vertical shaft, having cranks at either end, mounted upon said section, means for turning said shaft, a forward section movable along the guide-shafts, and links connecting said forward section to said cranks, substantially as set forth. 115
8. In a wire-fence machine, a rear section supported upon a shoe, and having an adjustable steadyng-wheel, a wheeled forward section, clutches carried by said forward section, and a crank-and-link connection between said sections, substantially as set forth. 125
9. In a wire-fence machine, a bobbin-holder, having a perforated wire-feeding stem adapted to intermesh with the cogs of the twister-wheels, substantially as set forth. 130
10. In a wire-fence machine, a bobbin-

- holder having a perforated wire-feeding stem projecting from the rear of the base-plate, said stem having a flanged end, substantially as set forth.
- 5 11. In a wire-fence machine, a bobbin-holder having a perforated wire-feeding stem, the sides of which are formed in the shape of a double cog-tooth, substantially as set forth.
12. In a wire-fence machine, a twister-wheel having one of its cogs removed, forming an additional space, and projections on either side of said space out of the plane of the cogs, substantially as set forth.
13. In a wire-fence machine, a twister-wheel having one of its cogs removed to form a space, and small auxiliary teeth upon each side of said space separate from each other and from the remaining cogs of the wheel, substantially as set forth.
- 20 14. In a wire-fence machine, a twister-wheel having one of its cogs removed to form a space, small auxiliary teeth upon either side of the said space in the plane of the main cogs, and projections upon either side of said space out of the plane of the cogs, substantially as set forth.
- 15 15. In a wire-fence machine, a twister-wheel having one of its cogs removed to form a space, and small auxiliary teeth upon either side of said space, said teeth being narrower than the main cog, and an intermeshing twister-wheel having two adjacent cogs cut away on one side to mesh with said auxiliary teeth, substantially as set forth.
- 35 16. In a wire-fence machine, the combination with a series of twister-wheels, each having a cog removed leaving a space, of a bobbin-holder having an apertured wire-feeding stem adapted to fit within said space, substantially as set forth.
- 40 17. In a wire-fence machine, a wheel having a cog removed, leaving a space, and a pair of diametrically-opposed openings in its web in line with said space, substantially as set forth.
- 45 18. In a wire-fence machine, the combination with a series of intermeshing twister-wheels, each having a cog removed, leaving a space, and a pair of diametrically-opposed openings in its web, of a series of bobbin-holders each having a wire-feeding stem adapted to fit within said spaces, and a pair of spring-pressed dogs adapted to engage the openings in adjacent wheels, substantially as set forth.
- 55 19. In a wire-fence machine, a series of in-
- termeshing twister-wheels, each having diametrically opposite openings in its web, and having one cog removed, leaving a space, in combination with a series of bobbin-holders, each having a base formed with openings in its opposite sides, a stem fitting said space, and a pair of spring-dogs hinged to the bobbin-holder and adapted to project into the openings in the base-plate and wheel whenever said openings are in register, substantially as set forth.
- 20 20. In a wire-fence machine, a series of intermeshing twister-wheels arranged upon hollow shafts, each wheel having a cog removed, leaving a space, and having a pair of diametrically-opposed openings in its web; a stationary disk surrounding each shaft in front of the wheels, said disks having concave upper and lower edges, bobbin-holders having bases provided with openings and arranged between said disks and wheels and having wire-feeding stems projecting through said spaces, and spring-dogs adapted to engage said openings in the wheels and bases, substantially as set forth.
- 25 21. In a wire-fence machine, a bobbin-holder consisting of a base-plate having curved upper and lower edges, openings near said edges, a rearwardly-projecting feed-stem, forwardly-projecting side arms, spring-dogs mounted in said arms and adapted to project into the openings in the plate, and a pair of bobbin-supporting clamps upon said arms, substantially as set forth.
- 30 22. In a bobbin-holder for wire-fence machines, a pair of spring-dogs pivoted to the frame of said holder, and having heads arranged to project through openings in the base, said heads each having a flange or stop adapted to rest against the base, a curved or inclined outer surface, and a straight inner surface, substantially as set forth.
- 35 23. In a wire-fence machine, the combination with a rotating shaft, of a worm upon said shaft, a pawl engaging said worm, and stop-pieces arranged in the path of the pawl to limit the rotation of the shaft, substantially as set forth.
- In testimony of all which I have hereunto subscribed my name.
